(57) **CLAIM**

The ornamental design for a vehicle seat, as shown and described.

DESCRIPTION

FIG. 1 is a front perspective view of a vehicle seat showing our new design;

FIG. 2 is a front view of the vehicle seat of FIG. 1;

FIG. 3 is a rear view of the vehicle seat of FIG. 1;

FIG. 4 is a right side view of the vehicle seat of FIG. 1;

FIG. 5 is a left side view of the vehicle seat of FIG. 1;

FIG. 6 is a top view of the vehicle seat of FIG. 1; and,
FIG. 7 is a rear perspective view of the vehicle seat of FIG. 1.

The broken lines shown in the drawings illustrate unclaimed portions of the vehicle seat and form no part of the claimed design.

The different surface shadings (line shading and stippled shading) in the drawings are used to indicate contrasting materials.
